UNITED STATES PATENT OFFICE.

LOUIS BAUMER, OF JOHNSTOWN, PENNSYLVANIA.

LOCK FOR STEP-LADDER CHAIRS.

SPECIFICATION forming part of Letters Patent No. 677,052, dated June 25, 1901.

Application filed March 29, 1901. Serial No. 53,495. (No model.)

To all whom it may concern:

Be it known that I, LOUIS BAUMER, a citizen of the United States, residing at Johnstown, in the county of Cambria, State of Pennsylvania, have invented certain new and useful Improvements in Locks for Step-Ladder Chairs, of which the following is a specification, reference being had therein to the accompanying drawings.

10 This invention relates to a lock for step-ladder chairs, and particularly to a device adapted to lock and hold the chair in either of its adjusted positions.

15 The invention has for its object to provide a lock comprising a single member simple in construction and operation, pivotally mounted upon a relatively fixed part of the chair and adapted to engage locking members carried by a movable portion of the chair when 20 in its different adjusted positions.

25 Other objects and advantages of the invention will hereinafter appear in the following description and the novel features thereof will be particularly pointed out in the appended claim.

30 In the drawings, Figure 1 represents the chair in the form of a step-ladder. Fig. 2 is a similar view with the parts arranged as a chair. Fig. 3 is an elevation of the locking device, and Fig. 4 is a longitudinal section of the locking device.

Like letters of reference indicate like parts throughout the several figures of the drawings.

35 The letter A designates a step-ladder chair, which may be of any ordinary and desired construction, composed of a section A', pivoted to the base A and carrying the rear or back leg A² and the back-supporting standards A³, while the portion A is provided with the front leg A⁴, which is always relatively fixed to the movable portion A' in its several adjusted positions. The fixed and movable portions of the chair are pivoted in any de-

40 sired manner—for instance, as shown at A⁵—so that when in the position shown in Fig. 1 a step-ladder is formed, while when folded into the position shown in Fig. 2 a chair is provided. The details of construction of these

parts are common in the art, and the invention is in no wise limited to the same.

45 The locking device B is provided at one end with a pivoting-socket B', and upon the opposite sides thereof locking-recesses B² and B³ are provided. In the structure shown recesses are used; but it will be obvious that any other desired engaging device may coöperate with the pins or projections C and C', secured, respectively, at the upper and lower portions of the standard, which forms the 50 back of the chair when in the position shown in Fig. 2. The locking device or plate may be provided with a stiffening-rib—for instance, as shown at B⁴—and suitably ornamented in any desired manner. This device is pivoted 55 to the relatively fixed member of the chair, preferably to the leg A⁴, by means of the aperture B' and adapted to swing upon that pivot, so as to bring either the recess B² in engagement with the pin C, Fig. 1, to lock the 60 parts in position as a ladder, or by swinging the plate completely over the recess B³ is brought into engagement with the pin C'. These recesses are shown as located at different 65 distances from the pivotal point of the 70 plate, which distances may be varied, dependent upon the distance of the locking-pins C' and C from the pivotal point B' of the locking 75 device B.

From the foregoing description the operation 80 of the parts will be clearly understood, and it will be further understood that the locking device is adapted to lock and hold the chair in either of its adjusted positions by a single simple plate so mounted upon a relatively fixed part as to engage separate and independent locking members upon a movable or adjustable part. It will further be seen that the device is of such a character that it can be applied to chairs of this construction now in use by the simple insertion 85 of a retaining-screw and the locking-pins for engagement with the plate.

Having described my invention, what is claimed is—

90 A step-ladder chair comprising relatively fixed and movable members, locking projections upon opposite end portions of said mov-

able member, a plate pivotally mounted upon said fixed member of the chair and provided upon its opposite faces with locking-sockets disposed at a distance from the pivotal point 5 to permit engagement with either of said projections to lock the chair in its adjusted positions; substantially as specified.

In testimony whereof I affix my signature in presence of two witnesses.

LOUIS BAUMER.
